(57) **CLAIM**

The ornamental design for a goggle frame, as shown and described.

DESCRIPTION

FIG. 1 is an isometric view of a goggle frame according to an embodiment of the design.

FIG. 2 is a front view of the goggle frame; and,

FIG. 3 is a left side view of the goggle frame, wherein a right side view of the goggle frame (not shown) is a mirror image of the left side view.

The broken line showing of the portions of the goggle frame is included for the purpose of illustrating the environment and forms no part of the claimed design.

1 Claim, 2 Drawing Sheets

FIG. 1

FIG. 2

FIG. 3
